UNITED STATES PATENT OFFICE.

JOHN PORTER, OF PITTSBURG, PENNSYLVANIA.

DESIGN FOR A SPINNING-TOP.

SPECIFICATION forming part of Design No. 31,655, dated October 10, 1899.

Application filed August 23, 1899. Serial No. 728,246. Term of patent 7 years.

To all whom it may concern:

Be it known that I, JOHN PORTER, a citizen of the United States of America, residing at Pittsburgh, in the county of Allegheny and State of Pennsylvania, have invented a certain new and useful Design for a Spinning-Top, of which the following is a specification, reference being had therein to the accompanying drawings.

10 This invention relates to certain new and novel designs in spinning-tops.

In the drawings, Figure 1 is a perspective view of my new design of spinning-top. Fig. 2 is a vertical sectional view of the same.

15 The invention comprises the unitary article made the subject of illustration as herein shown; and it consists of a top formed of a

cylindrical body portion 1 and a cone-shaped base 2. A series of ridges 3 extend circumferentially around the body portion, the contour lines of said ridges being semicircular in cross-section, said semicircular lines being connected by vertical lines 4.

What I claim as new, and desire to secure by Letters Patent, is—

20 The design for a spinning-top, substantially as shown and described.

25 In testimony whereof I affix my signature in the presence of two witnesses.

JOHN PORTER.

Witnesses:

JOHN NOLAND,
WILLIAM E. MINOR.
